SOUND RECORDING SYSTEM

Richard Schmidt, Dessau in Anhalt, Germany,
assignor to Agfa Ansco Corporation, Binghamton, N. Y., a corporation of New York

Application May 13, 1932, Serial No. 611,185
In Germany May 19, 1931

2 Claims. (Cl. 179—100.3)

My present invention relates to the production of sound records.

One of its objects is a device for producing photographic sound records of varying intensity, wherein sound vibrations are used to vary, by way of an electromagnetic process, the width of an exposure slit. Further objects will be seen from the detailed specification following hereafter. Reference is made to the accompanying drawing 10 in which:

Fig. 1 is a plan view of the device according to this invention, and

Fig. 2 is an end view thereof.

Fig. 3 shows the same view as Fig. 2 but the 15 device being provided with means to secure a constant distance of the poles *a* and *a'*.

The device consists of a magnet, between the poles *a* and *a'* of which a tongue *b* is arranged 20 parallel to the limbs of the magnet. The tongue *b* is fastened to a slotted square support of brass *g*, by means of screw *i* and screw nut *k* and is caused to oscillate in the magnetic field by reason 25 of electric current impulses received by the stationary coils *c* and *c'* through which the tongue passes and which transmits these current variations to the tongue. The stationary coils *c* and *c'* receive their current impulses 30 by the action of the sound vibrations which are recorded by the sound receiving device (not illustrated). The tongue *b* carries a blade *d* which 35 faces a second blade *e* fixed to one of the poles of the magnet. Beneath the tongue *b* there are arranged the source of light *f*, for instance, an incandescent lamp, and a concave mirror *h*. By 40 the action of the sound vibrations, the tongue *b* oscillates, and the exposure slit formed by the two blades *d* and *e* is alternately widened and narrowed. On a photographic film travelling immediately behind the exposure slit there are thus 45 produced more or less intense latent photographic images.

If with this arrangement an expansion of the metal parts, due to the radiation of heat from the source of light, is to be feared, the magnet 50 may be provided with compensating strips of a different metal or the whole device may be fixed on a rigid frame preventing any expansion.

On account of the heat radiation of the glow lamp the magnet may be so strongly heated that 55 it is somewhat bent open whereby the slit between the blades *d* and *e* may be unduly enlarged. In order to prevent this drawback the poles *a* and *a'* may be united to a rigid frame by means of an unmagnetizable material, for instance, brass. 60 Such an arrangement is shown in Fig. 3 wherein the poles *a* and *a'* are on both sides surrounded by blocks *n* of brass united with the same to a rigid frame by means of screws *s* and screw nuts *r*. In another arrangement the magnet is given on 65 its inner side a support *m* (cf. Fig. 1) of a material

having a low expansibility, for instance, a nickel steel containing about 36 per cent of nickel, the so-called invar, the expansibility of which amounts to less than 1 per cent of that of iron. In the case of heating an increased bent is produced which by suitably selecting the support of invar just compensates the undesired change of form.

The slit can be protected from dust by extending over the blades an elastic transparent membrane of any colloidal material, for instance, a film of a cellulose derivative or of regenerated cellulose, or by arranging over the blades a very thin lamina of glass, quartz or the like. The covering must, of course, be arranged in a way that it does not hinder the oscillation of the blade fixed to the tongue *b*. In Fig. 1, for instance, the elastic membrane *l* covers the blades *d*, *e*. It is pasted to the blade *d* and the limb *a'* of the magnet, the distance between the places of attachment to the blade and the limb being sufficiently great so that the oscillation of the blades is not hindered.

The device presents the considerable advantage 85 of being highly sensitive so that it is even possible to produce the record without the usual amplification by tubes. It is, of course, possible to combine the device with the known amplifying tubes, if desired.

What I claim is:

1. A device for producing photographic sound 90 records of varying intensity which comprises a magnet having two limbs, one of said limbs being provided with a blade, a tongue arranged between and parallel to said limbs and provided with a blade forming a slit with said blade of said magnet, said tongue being provided with stationary 95 field coils causing said tongue to oscillate on electric impulses communicated to said coils, and a source of light arranged between the limbs of said magnet.

2. A device for producing photographic sound 100 records of varying intensity which comprises a magnet having two limbs, one of said limbs being provided with a blade, a tongue arranged between and parallel to said limbs and provided with a blade forming a slit with said blade of said magnet, said tongue being provided with stationary field coils causing said tongue to oscillate on electric impulses communicated to said coils, and a source of light and a concave mirror being arranged between the limbs of said magnet, said 105 mirror being arranged behind said source of light, remote from said slit.
